DIRECTION INDICATOR FOR A BICYCLE

Colin Cameron Smades, 43 Victoria Ave., Milton,
Ontario, Canada

Filed May 6, 1963, Ser. No. 74,745

Term of patent 3½ years

(Cl. D48—32)

FIG. 1 is a reduced perspective view of a direction indicator for a bicycle embodying my new design, with fragmentary portions of a bicycle shown in broken line for illustrative purposes only.

FIG. 2 is a front elevational view of the direction indicator;

FIG. 3 is a top plan view thereof;

FIG. 4 is a rear elevational view thereof; and

FIG. 5 is an end view thereof.

The characteristic features of my design reside in the appearance afforded by the elongated horizontal support having a forward, arcuate linear edge and angularly related symmetrical rear edges, and the elements extending vertically at the terminal ends of said support and disposed intermediately of the conventional, egg-shaped lamp housing all as shown.

I claim:

The ornamental design for a direction indicator for a bicycle, as shown and described.
